UNITED STATES PATENT OFFICE.

JOHN WM. DAVIS, OF JANESVILLE, WISCONSIN.

SHUTTLE-BINDER FOR LOOMS.

SPECIFICATION forming part of Letters Patent No. 446,113, dated February 10, 1891.

Application filed May 3, 1890. Serial No. 350,462. (No model.)

To all whom it may concern:

Be it known that I, JOHN WILLIAM DAVIS, a citizen of the United States, residing at Janesville, in the county of Rock and State of Wisconsin, have invented new and useful 5 Shuttle-Binders for Looms, of which the following is a specification.

This invention has relation to shuttle-binders for looms; and it has for its object to construct a device of this class which shall be effective and certain in operation.

With these ends in view the invention consists in the improved construction, arrangement, and combination of parts, which will 15 be hereinafter fully described, and particularly pointed out in the claims.

In the drawings, Figure 1 is a perspective view showing my improved shuttle-binder detached from the shuttle-box. Fig. 2 is a 20 side view of a shuttle-box equipped with my improved binder, showing also a portion of the protector mechanism of a loom. Fig. 3 is a top view of the same. Fig. 4 is a detail end view. Fig. 5 is a sectional view taken on the 25 line 5 5 in Fig. 1.

Like numerals of reference indicate like parts in all the figures.

1 designates the shuttle-box, and 2 is the 30 protector-rod, which is provided with the finger 3 and with the arm or dagger 4, which is adapted to engage the recess 5 in the bunter 6 for the purpose of moving the latter and causing it to operate to stop the loom when the shuttle fails to properly enter the box. The 35 construction of these parts is common to many looms, and, as they form no part of my present invention, their position with relation to the shuttle-box has been merely indicated in the drawings without entering into their 40 detailed construction.

7 designates the binder, which is composed of two parts or sections, designated, respectively, by 8 and 9. The part 8 is hinged in the usual manner by means of a transverse pin 45 10 near the outer end of the shuttle-box, and the part 9 is hinged by means of a transverse pin 11 between a pair of lugs or flanges 12 at the inner end of the part 8. The latter is provided with a recess 13 to accommodate the inward-extending arm 14 of the 50 member 9, and the same arm 14 is provided

at its outer end with a recess 15 to accommodate the free end of the spring 16, which is secured in the usual manner to the shuttle-box, and which serves to keep the binder in 55 its proper position. The inner end of the member 9 of the binder is provided with the flanges 17 to rest against the outer side 22 of the shuttle-box when the shuttle is out. The outward movement of the point of the binder 60 is limited by the transverse pin 18 of the shuttle-box. The inner side of the part or member 8 of the binder is provided with a longitudinal groove 19 for the passage of the filling as it unwinds from the bobbin in the 65 shuttle.

The operation of my invention and its advantages will be readily understood from the foregoing description, taken in connection with the drawings hereto annexed, by those 70 skilled in the art to which it appertains. When the shuttle properly enters the box, the binder will move in an outward direction in the usual manner, as will be readily understood. If, on the other hand, the shuttle fails 75 to enter the box in time to throw out the protector-rod finger 3 to trip the arm or dagger 4 to pass the bunter, the dagger will engage the recess 5 of the latter and throw the stop mechanism into action, one of the results being that the finger 3 will press the point of 80 the binder firmly against the outer side 22 of the shuttle-box. The shuttle in the meanwhile continues its course, and, owing to the fact that my improved binder is composed of 85 two parts or members flexibly connected, it will be permitted to enter the box without danger of breakage, although the point of said binder is held almost rigidly by the finger 3, while, when a binder consisting of a 90 single piece is used, either the binder or the shuttle will be almost certainly broken. By my improvement I avoid the danger of breakage and the expense and loss of time caused under these circumstances. 95

Having thus described my invention, I claim—

1. The combination, with a shuttle-box, of a binder composed of an arm hinged in said shuttle-box and provided at its inner end 100 with lugs or flanges and a member hinged between said lugs or flanges carried by and

moving with the said arm and having an outwardly-extending arm provided at its outer end with a recess, and the holding-spring having a bearing in said recess for its free end, 5 substantially as set forth.

2. The herein-described shuttle - binder, composed of the members 8 and 9, the former being provided with the recess 13 and longitudinal groove 19 and the latter having the 10 flanges 17 and outwardly-extending arm 14,

provided with the recess 15, said parts or members being hinged together, substantially as and for the purpose herein set forth.

In testimony that I claim the foregoing as my own I have hereto affixed my signature in 15 presence of two witnesses.

JOHN WM. DAVIS.
